UNITED STATES PATENT OFFICE

102,804

DESIGN FOR INSTRUMENT FOR LOCATING DISPLACED VERTEBRA OF THE SPINE

Herand Robinson, Columbus, Ohio

Application December 24, 1935, Serial No. 60,268

Term of patent 7 years

To all whom it may concern:

Be it known that I, Herand Robinson, a citizen of the United States, residing at Columbus, in the county of Franklin and State of Ohio, have invented a new, original, and ornamental Design for an Instrument for Locating Displaced Vertebra of the Spine, of which the following is a specification, reference being had to the accompanying drawing, forming part thereof.

Fig. 1 is a front view of an instrument for locating displaced vertebra of the spine showing my new design;

Fig. 2 is a side view thereof; and

Fig. 3 is a rear view thereof.

I claim:

The ornamental design for an instrument for locating displaced vertebra of the spine, as shown.

HERAND ROBINSON.
